US0D1023558S

(12) **United States Design Patent** (10) **Patent No.:** **US D1,023,558 S**
(45) **Date of Patent:** **** Apr. 23, 2024**

(54) **BACKPACK**

(71) Applicant: **Weihang Xu**, Guangzhou (CN)
(72) Inventor: **Weihang Xu**, Guangzhou (CN)
(*) Notice: Patent file contains an affidavit/declaration under 37 CFR 1.130(b).

(**) Term: **15 Years**

(21) Appl. No.: **35/517,305**

(22) Filed: **May 8, 2023**

(80) **Hague Agreement Data**

Int. Filing Date: **May 8, 2023**

Int. Reg. No.: **DM/228930**

Int. Reg. Date: **May 8, 2023**

Int. Reg. Pub. Date: **May 26, 2023**

(51) **LOC (14) Cl.** 03-01

(52) **U.S. Cl.**

USPC **D3/217**

(58) **Field of Classification Search**

USPC D3/216–217, 225, 226, 230–232,

Assistant Examiner — Dustin Andrew Griffith

(57) **CLAIM**

The ornamental design for a backpack, as shown and described.

DESCRIPTION

- 1. Backpack
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Enlarged
- 1.10 : Enlarged
- 1.11 : Enlarged
- 1.12 : Enlarged
- 1.13 : Enlarged
- 1.14 : Enlarged

The parts shown by means of broken lines in the reproductions are not part of the claimed design; fig. 1.9, 1.10, 1.11, 1.12, 1.13, 1.14 are the enlarged views of the portion taken at line 9 in fig. 1.1, line 10 in fig. 1.2, line 11 in fig. 1.5, line 12, 13 in fig. 1.7, line 14 in fig. 1.8; the dash dot dash lines in the reproductions and the number “9”, “10”, “11”, “12”, “13”, “14” in fig. 1.1, 1.2, 1.5, 1.7, 1.8 are for the purpose of depicting the cut line of the enlarged view and form no part of the claimed.

1 Claim, 14 Drawing Sheets
